(57) CLAIM

We claim the ornamental design for a shelf for an outdoor cooking device, as shown and described.

DESCRIPTION

FIG. 1 is a perspective view of a shelf for an outdoor cooking device showing our new design, the details shown in broken lines are for illustrative purposes only and form no part of the claimed design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof; and,

FIG. 7 is a side elevational view of the opposite side of FIG. 6.
